G. W. ABRAHAM

PADDLE

Filed June 11, 1923

Inventor:

George William Abraham

By *Richard T. Dabell*

Attorneys

UNITED STATES PATENT OFFICE.

GEORGE WILLIAM ABRAHAM, OF DETROIT, MICHIGAN.

PADDLE.

Application filed June 11, 1923. Serial No. 644,563.

To all whom it may concern:

Be it known that I, GEORGE WILLIAM ABRAHAM, a citizen of the United States of America, residing at Detroit, in the county 5 of Wayne and State of Michigan, have invented certain new and useful Improvements in Paddles, of which the following is a specification, reference being had therein to the accompanying drawings.

10 This invention relates to a paddle for use with canoes or small boats. It consists essentially of a paddle blade of the type ordinarily used for canoe paddles, the blade being provided with a handle having a 15 hand-grip of the type usual with canoe paddles, and the blade having at a considerable distance from its outer end an opening within which is mounted a small propeller, the shaft of which extends axially of the 20 handle to an electric motor, the casing of which forms a portion of the handle.

The principal object of the invention is to provide a paddle of light weight capable of all the uses of an ordinary canoe paddle, but 25 having in addition a propeller of such small size as to be capable of operation by a light weight motor of a type suitable for use with an ordinary storage battery of small size.

Another object of the invention is to provide a motor driven propeller for use with canoes in streams or the lagoons of parks or other places where the use of gas engines 30 is prohibited.

Other and further objects will appear in 35 connection with the description of the embodiment of the invention illustrated in the accompanying drawing, in which—

Figure 1 is a perspective view of the 40 paddle showing the connection of its motor with a storage battery, and

Fig. 2 is a fragmentary side elevation on an enlarged scale.

In many parks having inclosed lagoons or 45 other waterways, on which canoeing is permitted, regulations have been made prohibiting the use of internal combustion motors either for boats provided with the ordinary screw propeller or for boats having the so-called outboard motors. The paddle herein 50 illustrated is designed to overcome the objections which have caused such regulations to be issued.

The blade 1 is preferably of wood and 55 made in any preferred shape suitable for use with a canoe. A handle portion 2 preferably integral with the blade has secured at

the end remote from the blade 1 a tubular portion 3 of the casing 4 of an electric motor. A second tubular portion in line with the portion 3 has secured therein the grip member 6 which may have any shape suitable for use with a canoe paddle.

An electric motor 7 within the casing 4 has a shaft 8 extending therefrom through a bore formed axially of the handle portion 2 and of the inner end of the blade 1, the end of the shaft terminating centrally of an opening 9 within the blade, and having secured upon its end a propeller 10. The opening 9 is at a point far enough away 60 from the outer end of the blade to permit free use of the paddle when the motor is not in operation, but when it is desired to use the propeller the blade will be submerged to a point at which the propeller is entirely 65 beneath the surface of the water and the motor may then be driven to cause rotation of the shaft 8 and of the propeller 10. The paddle will be held by the occupant of the 70 canoe with the blade portion projecting toward the rear so that the unobstructed portion beyond the propeller will serve as a rudder by which the course of the canoe 75 may readily be directed. The motor 7 will be of a type small enough to be driven 80 economically by a storage battery 11 of the type in common use in automobiles, which has a standard current strength of about six volts. The propeller blade 10 will prefer- 85 ably be of a metal not subject to corrosion, and for ordinary use, its extreme length 90 need not exceed three inches.

A propeller of the size indicated will be 95 larger in proportion to the size of a canoe and the weight carried thereby, than is the propeller of an ordinary steamship in proportion to the size of the vessel with which it is to be used and the cargo customarily carried by such a vessel.

It will be evident from the foregoing 100 description that the device can be produced at a low cost and that the expense of operation will be small. The motor is light and completely inclosed within the casing so that it cannot do any bodily harm to the user 105 while it is in operation. Furthermore, the device is substantially noiseless, even when operating at full speed. With the casing 4 constructed of aluminum, the additional weight, due to the use of the propeller with 110 its shaft and motor, is only a little greater than that of an ordinary paddle, while its

adaptation for multiduty purposes renders it much more desirable than the ordinary paddle.

It will be obvious that many changes in size, proportion and specific details of construction of the parts may be made without departing from the principle of my invention or sacrificing any of the advantages thereof. I wish therefore to claim my invention broadly within the full and legitimate scope of the appended claim.

I claim:

A paddle particularly adapted for the paddling of canoes having a blade, a handle and an intermediate grip member, said grip member being tubular and said blade provided with an opening remote from the end thereof and adjacent the tubular grip mem-

ber, a motor housing located between and connected to opposed ends of said handle and said grip member, an electric motor completely enclosed in said motor housing, a shaft extending from said motor through said grip member to the opening in said blade, and a propeller mounted on the end of said shaft within said opening, the arrangement of parts being such that said motor is situated intermediate the hands of a person grasping said paddle as and for the purpose as specified.

In testimony whereof I affix my signature in presence of two witnesses.

GEORGE WILLIAM ABRAHAM.

Witnesses:

ARTHUR MINNICK,
G. L. TERRA.
